CORNER GRINDING MACHINE

Peter J. Kirkman, Ottawa, Ill., assignor to Libbey-Owens-Ford Glass Company, Toledo, Ohio, a corporation of Ohio

Application June 25, 1938, Serial No. 215,713

5 Claims. (Cl. 51—40)

The present invention relates to grinding machines in general and more particularly to an improved machine for grinding the corners of sheets or plates of glass and the like to remove the rough or sharp edges and obtain smooth, well finished surfaces.

An important object of the invention is the provision of a machine of this character effective for grinding two opposite corners of the glass sheets or plates simultaneously and in a rapid, accurate, and economical manner.

Another important object of the invention is the provision of a machine of this character which is of relatively simple, inexpensive construction, yet positive and efficient in operation and which will serve to grind the opposite corners of the glass sheets or plates evenly and uniformly.

Other objects and advantages of the invention will become more apparent during the course 20 of the following description when taken in connection with the accompanying drawings.

In the drawings wherein like numerals are employed to designate like parts throughout the same:

25 Fig. 1 is a side elevation of a grinding machine constructed in accordance with this invention; Fig. 2 is a top plan view thereof;

Fig. 3 is a longitudinal vertical section through a portion of the supporting frame taken substantially on line 3—3 of Fig. 2;

Fig. 4 is a vertical section through the means for supporting the sheets during grinding, taken substantially on line 4—4 of Fig. 1;

Fig. 5 is a vertical section through one of the 35 pivotally mounted runway sections taken substantially on line 5—5 of Fig. 1; and

Fig. 6 is a vertical section through another portion of the pivoted runway section taken substantially on line 6—6 of Fig. 1.

40 With reference to the drawings, the grinding machine is designated in its entirety by the numeral 10 and comprises briefly a vertically movable supporting frame 11 upon which are mounted the vertical grinding wheels 12 and 13. The 45 grinding wheels are horizontally spaced from one another and positioned to rotate about horizontal axes, each grinding wheel being preferably provided in its periphery with a plurality of grooves 14 for receiving the corners of the sheets or plates 50 of glass or the like 15 to be ground. The glass sheets are supported on edge in a vertical position above the grinding wheels 12 and 13 by the supporting means designated in its entirety by the numeral 16.

55 The glass sheets 15 are preferably maintained

stationary during grinding while the grinding wheels 12 and 13 are movable vertically into engagement with the two opposite corners *a* and *b* of the said sheets to effect the grinding of said corners simultaneously. The corners *a* of the sheets are received in the grooves 14 of grinding wheel 12 and the corners *b* in the grooves of grinding wheel 13. After the glass sheets have been properly ground, the grinding wheels are lowered out of engagement with the sheets to 10 permit the removal thereof and the positioning of another group of sheets to be treated.

More specifically, the supporting frame 11 is substantially rectangular both in side elevation and top plan and is slidably mounted upon vertical posts 17 provided at the four corners thereof. As best shown in Fig. 3, there is arranged within each corner of the supporting frame, the vertically spaced bracket plates 18 and 19 provided with openings for loosely receiving the respective post 17 therethrough. To assist in supporting the frame 11 and also to facilitate the raising and lowering thereof, there may be provided at each of the four corners of said frame a counterweight 20. Each counterweight is attached to one end 25 of a sprocket chain 21 which passes upwardly over a sprocket 22 and is fastened at its opposite end to a bolt or the like 23, said bolt passing through an arm 24 fixed to the supporting frame 11 and being secured thereto by nuts 25. The 30 sprockets 22 at one end of the frame are loosely mounted upon a transverse shaft 26 while the sprockets 22 at the opposite end of said frame are loosely mounted upon a similar transverse shaft 27. Each of the shafts 26 and 27 is supported at 35 its opposite ends in bracket arms 28 and 29 secured to the opposite ends of a flat plate 30 carried upon the tops of the opposed posts 17 and fastened thereto in any suitable manner such as by means of the bolts 31 and nuts 32.

The means for raising and lowering the supporting frame 11 comprises an air or hydraulically operated cylinder 33 adapted to be controlled by the operator. The piston 34 of said cylinder 33 has attached to its outer end two sprocket chains 35 and 36. The sprocket chain 35 passes upwardly over a sprocket 37 (Fig. 3) mounted upon a horizontal stub shaft 38 carried by a bracket 39 fixed to the frame 11. The sprocket chain 35 continues upwardly over a second sprocket 40 45 carried by the transverse shaft 26 and is fastened at its opposite end, by means of a bolt 41 and nuts 42, to an arm 43 fixed to the frame 11. The sprocket chain 36 passes over a sprocket 44 also carried by the stub shaft 38 and about a second 50

sprocket 45 mounted upon the bracket 39. The sprocket chain then extends horizontally to the opposite end of the frame where it passes upwardly first over a sprocket 46 carried by bracket 5 47 and then over a sprocket 48 mounted upon transverse shaft 27. The sprocket chain is fastened at its end to an arm 49 fixed to frame 11. With this arrangement, it will be seen that upon 10 operation of the cylinder 33 to retract the piston 10 34, the supporting frame 11 and grinding wheels 12 and 13 carried thereby can be moved upwardly upon the vertical rods 17 whereas when the piston 34 is moved outwardly, the said frame and grinding 15 wheels will be lowered.

15 The grinding wheels 12 and 13 are mounted upon horizontal transverse shafts 50 and 51 respectively, each being journaled at its opposite ends in bearings 52 and 53. The grinding wheels 12 and 13 are driven by motors 54 and 55 respectively, the shaft 56 of each motor carrying a drive pinion 57 meshing with a spur gear 58 fixed to the respective grinding wheel shaft 50 or 51.

20 The supporting means 16 for the glass sheets 15 comprises a longitudinally extending, U-shaped channel member having a bottom 59 and the vertical side members 60 and 61, said channel member being supported at the opposite ends of the supporting frame upon standards or the like 25 62. Mounted within the channel member, between the two grinding wheels, is a stationary block 63 to the upper surface of which is secured a pad 64 of rubber or the like having a plurality of grooves therein for receiving the bottom edges 30 of the glass sheets 15. As shown, the length of the glass sheets is greater than the length of the supporting block 63 so that the corners *a* and *b* to be ground project therebeyond.

35 The bottom 59 of the channel member is cut 40 away at opposite sides of the supporting block 63 to provide slots 65 and 66 through which the upper portions of the grinding wheels 12 and 13 are adapted to project when they are moved upwardly to engage the corners *a* and *b* of the glass 45 sheets as indicated by the broken lines in Fig. 1. Mounted within the channel member at opposite sides of the supporting block 63 are the roller runway sections 67 and 68 provided with the supporting rollers 69 and 70 over which the glass 50 sheets can be moved to and from grinding position. The rollers of each runway section are preferably provided with grooves 71 aligning with the grooves in supporting block 63 and are carried by shafts 72 mounted at their opposite ends 55 in side members 73 and 74 respectively. Each roller runway section is pivotally mounted at the end thereof remote from the sheet supporting block 63, and this is accomplished by extending the shaft 72 of the end roll through the side 60 members 60 and 61 of the channel member as shown in Fig. 5. During the movement of the glass sheets into or out of grinding position, the pivotized runway sections 67 and 68 are disposed in horizontal position as indicated by the full 65 lines in Fig. 1, at which time the grooves 71 in the rollers 69 and 70 are in horizontal alignment with the grooves in the sheet supporting block 63.

70 Upon raising of the grinding wheels 12 and 13 to effect the grinding of the corners *a* and *b* of the glass sheets 15, the runway sections 67 and 68 are adapted to be automatically raised to broken line position so as not to interfere with the proper grinding of the sheets. For this purpose, there is pivoted to one roll of each of the runway sections 67 and 68 an arm 75, the opposite end being

pivoted to the shaft 50 or 51 of the respective grinding wheel or to any other part of the frame 11. Thus, it will be seen that as the frame 11 is raised to move the grinding wheels upwardly to grinding position, the arms 76 will simultaneously swing the inner adjacent ends of the runway sections upwardly out of the way.

15 In operation, the supporting frame 11 is normally maintained in a lowered position with the grinding wheels 12 and 13 below the supporting means 16 and the pivoted runway sections 67 and 68 in horizontal alignment with one another. The glass sheets 15 to be ground are then properly placed upon the supporting block 63 and while held in such position, either by the operator or in any other desired manner, the frame 11 is raised to bring the grinding wheels 12 and 13 into engagement with the two opposite corners *a* and *b* of the said sheets to grind the same simultaneously. Upon raising of the grinding wheels, 20 the runway sections 67 and 68 will be swung upwardly out of the way as explained above. After the corners of the glass sheets have been properly ground, the supporting frame 11 is lowered to move the grinding wheels out of engagement with 25 the sheets and to again bring the runway sections 67 and 68 into horizontal alignment with one another. The ground sheets 15 can then be removed and a new group of sheets to be treated arranged in grinding position. The amount of 30 material removed from the corners of the sheets or, in other words, the extent of the grinding operation can be varied by controlling the raising movement of the supporting frame.

35 The grinding apparatus herein provided can be either used in connection with the so-called Weber type of edging machine to receive the glass sheets therefrom or it can be employed by itself as an individual machine. As shown, there is mounted outwardly of the roller runway section 40 67 a plurality of horizontally aligned conveyor rolls 76 and at the outer side of runway section 68, a plurality of similar horizontally aligned conveyor rolls 77. If the grinding apparatus is arranged at the end of a Weber type machine 45 to receive the glass sheets therefrom, the conveyor rollers 76 will be arranged in horizontal alignment with the conveyor rollers of said Weber machine. After the corners *a* and *b* of the glass sheets 15 have been properly ground, the sheets 50 can be moved over the rollers 70 of the runway section 68 and thence over the conveyor rollers 77 to the desired location or to another machine where the sheets can be further treated.

55 It is to be understood that the form of the invention herewith shown and described is to be taken as the preferred embodiment of the same, and that various changes in the shape, size and arrangement of parts may be resorted to without departing from the spirit of the invention or 60 the scope of the subjoined claims.

I claim:

1. In a machine for grinding the corners of sheets or plates of glass and the like, means for supporting the sheet to be ground, movably mounted runway sections leading to and from said sheet supporting means and over which the sheet can be moved into and out of grinding position, a pair of rotatable grinding wheels, means for effecting relative movement between said sheet supporting means and grinding wheels to bring the said grinding wheels into engagement with two opposite corners of the said sheet to grind the same simultaneously, and means for moving said runway sections out of normal po- 75

sition upon relative movement between said sheet supporting means and grinding wheels so as not to interfere with the grinding operation.

2. In a machine for grinding the corners of sheets or plates of glass and the like, means for supporting the sheet in a substantially fixed position, movably mounted runway sections disposed at opposite sides of said sheet supporting means and over which the sheet can be moved into and out of grinding position, a pair of rotatable grinding wheels, means for moving said grinding wheels to engage two opposite corners of the said sheet to grind the same simultaneously, and means for moving said runway sections out of normal position upon movement of said grinding wheels so as not to interfere with the grinding operation.

3. In a machine for grinding the corners of sheets or plates of glass and the like, means for supporting the sheet on edge in a substantially fixed position, pivotally mounted runway sections disposed at opposite sides of said sheet supporting means and over which the sheet can be moved into and out of grinding position, a pair of horizontally spaced, rotatable grinding wheels mounted beneath said sheet supporting means, means for raising said grinding wheels to engage two opposite corners of the said sheet to grind the same simultaneously, and means for swinging said runway sections upwardly upon raising of said grinding wheels so as not to interfere with the grinding operation.

4. In a machine for grinding the corners of sheets or plates of glass and the like, means for supporting the sheet on edge in a substantially fixed position, pivotally mounted runway sections

disposed at opposite sides of said sheet supporting means and over which the sheet can be moved into and out of grinding position, a vertically movable supporting frame arranged beneath said sheet supporting means, a pair of horizontally spaced, vertical grinding wheels mounted upon said frame, means for driving said grinding wheels, means for raising said frame to bring said grinding wheels into engagement with two opposite corners of the said sheet to grind the same simultaneously, and means actuated by raising movement of said frame to swing said runway sections upwardly so as not to interfere with the grinding operation.

5. In a machine for grinding the corners of sheets or plates of glass and the like, means for supporting the sheet on edge in a substantially fixed position, pivotally mounted runway sections arranged at opposite sides of said sheet supporting means and over which the sheet can be moved into and out of grinding position, a vertically movable supporting frame arranged beneath said sheet supporting means, a pair of horizontally spaced, vertical grinding wheels mounted upon said frame, means carried by said frame for driving said grinding wheels, means for raising said frame to bring said grinding wheels into engagement with two opposite corners of the said sheet to grind the same simultaneously, means for counterbalancing said frame, and operative connections between said frame and said runway sections for swinging the said runway sections upwardly upon raising of the said frame so as not to interfere with the grinding operation.

PETER J. KIRKMAN. 35
